(57) **CLAIM**

The ornamental design for an adjustable bracket, as shown and described.

DESCRIPTION

FIG. 1 is a left front perspective view of a single shaft embodiment of an adjustable bracket showing my new design.

FIG. 2 is a right side view of the adjustable bracket of FIG. 1.

FIG. 3 is a left side view of the adjustable bracket of FIG. 1.

FIG. 4 is a top view of the adjustable bracket of FIG. 1.

FIG. 5 is a front view of the adjustable bracket of FIG. 1; the rear view of the adjustable bracket of FIG. 1 is the mirror image of FIG. 5.

FIG. 6 is a bottom view of the adjustable bracket of FIG. 1. FIG. 7 is an exploded left front perspective view of the adjustable bracket of FIG. 1. The broken line showing of a partial pole of FIG. 7 is for illustrative purposes only and forms no part of the claimed design.

FIG. 8 is a front exploded view of the adjustable bracket of FIG. 1.

FIG. 9 is a right side exploded view of the adjustable bracket of FIG. 1.

FIG. 10 is a left side exploded view of the adjustable bracket of FIG. 1.

FIG. 11 is a top view of a component indicated in FIGS. 8 and 23 at "11-11".

FIG. 12 is a bottom view of the component indicated in FIGS. 8 and 23 at "12-12".

FIG. 13 is a bottom view of the component indicated in FIGS. 8 and 23 at "13-13".

FIG. 14 is top view of the component indicated in FIGS. 8 and 23 at "14-14".

FIG. 15 is left front perspective view of a double shaft embodiment of an adjustable bracket showing my new design.

FIG. 16 is a right side view of the adjustable bracket of FIG. 15.

FIG. 17 is a left side view of the adjustable bracket of FIG. 15.

FIG. 18 is a top view of the adjustable bracket of FIG. 15.

FIG. 19 is a front view of the adjustable bracket of FIG. 15; the rear view of the adjustable bracket of FIG. 15 is the mirror image of FIG. 19.

FIG. 20 is a bottom view of the adjustable bracket of FIG. 15.

FIG. 21 is an exploded left front perspective view of the adjustable bracket of FIG. 15. The broken line showing of a partial pole of FIG. 21 is for illustrative purposes only and forms no part of the claimed design.

FIG. 22 is a left side exploded view of the adjustable bracket of FIG. 15; and,

FIG. 23 is a front exploded view of the adjustable bracket of FIG. 15.
